Primary Examiner — Selina Sikder(74) *Attorney, Agent, or Firm* — SAIDMAN DesignLaw Group(57) **CLAIM**

The ornamental design for a light emitting diode, as shown and described.

DESCRIPTION

FIG. 1 is a front, top, left side perspective view of a first embodiment of a light emitting diode showing my new design;

FIG. 2 is a rear, bottom, right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines illustrate environmental structure and form no part of the claimed design.

The groups of two or three parallel lines on the top surface represent transparency.
